CLAIM

The ornamental design for an orthotic insert for footwear, as shown and described.

DESCRIPTION

FIG. 1 is a perspective view of a first embodiment of an orthotic insert for footwear showing our new design;

FIG. 2 is a top view thereof;

FIG. 3 is a bottom view thereof;

FIG. 4 is a side view thereof;

FIG. 5 is an opposite side view thereof;

FIG. 6 is a front view thereof;

FIG. 7 is a rear view thereof; and,

FIG. 8 is a perspective view of a second embodiment of an orthotic insert for footwear showing our new design.

The broken lines shown in the drawings represent portions of an orthotic insert for footwear that form no part of the claimed design.
